UNITED STATES PATENT OFFICE.

JAMES F. LOUCKS, OF CLEVELAND, OHIO, ASSIGNOR TO HOLORIB, INC., OF CLEVELAND,
OHIO, A CORPORATION OF OHIO.

CLAMPING DEVICE.

Application filed October 18, 1926. Serial No. 142,320.

This invention relates to clamping devices, sheet and to be bent over to secure the same 55 and more particularly to devices which are adapted for the purpose of securing metal sheets to structural beams.

5 The general object of the invention is to provide a simple, economical, and efficient clamping device of the character and for the purpose set forth. Further objects of the invention will appear hereinafter and will 60 be realized by the construction and arrangement of parts illustrated in the drawings, wherein Fig. 1 represents a sectional view through a sheet-metal structure, showing the 65 same secured to a structural beam by means 10 of clamps embodying my invention; Fig. 2 a detail in plan of one of the clamps shown in the preceding view, together with a portion of the beam to which it is applied; Fig. 3 a detail in section corresponding to the line 3—3 of Fig. 1; and Fig. 4 a perspective view 70 of the clamp.

Describing the various parts by reference characters, 1 denotes the web and 2 the flange of a structural beam. The beam may be an 75 angle beam or a channel beam. Supported by this beam is a building-construction unit, the same comprising a metal sheet 3 having projecting downwardly therefrom a plurality of hollow ribs, one of which is indicated 80 at 4, the said ribs being triangular in section and the tops of the ribs being substantially closed, whereby the surface of the sheet 3 will be substantially continuous or uninterupted while the bottom of the same 85 will be provided with triangular ribs which are adapted to be supported upon the tops of structural beams. The details of construction of the structural units and the purposes and advantages of the same are set 90 forth at length in the patent granted to Harry Gillet and myself on February 23, 1926, No. 1,574,586, the clamping means 95 shown herein being particularly well adapted for securing units or sheets of this general character to and spacing them from structural beams therebeneath.

Each clamp is made of sheet metal and comprises a substantially flat base adapted 100 to rest on top of a structural beam, a flange 105 projecting upwardly from said base and forming at its top edge a support for the bottom of a metal sheet, the top edge of the said flange being provided with a pointed tongue adapted to be pressed through the

against the top of the flange; the flange being continued downwardly in a vertically extending web or flange beyond one end of the said base and being provided at its lower end with a hook adapted to engage the under surface of one edge of the top flange of the beam, the opposite end of the base being adapted to be folded down into engagement with the opposite edge or web of the top of the beam.

The clamp is formed from a single piece of metal, the base portion referred to being shown at 5 and the vertical flange at 6, the said flange having the upper edge 6^a adapted to engage the bottom of the sheet 3 and the pointed tongue 7 projecting upwardly from the edge 6^a, the said tongue being adapted to be pressed or punched through the sheet 3 and folded down on top of the same, as shown in Figs. 1 and 3, thereby to secure the 75 bottom of the sheet firmly against the top of the flange 6.

The base 5 projects beyond the tongue-carrying end of the flange 6 and is of sufficient length to extend beyond the upper edge of the web 1 and to be bent downwardly in engagement therewith, as shown at 5^a in Fig. 3. The opposite end of the base is cut away on a line approximating an S, as shown at 5^b, and the metal beyond such cut 80 is bent downwardly to form an angular projection extending from the vertical web or extension 8 of the flange 6. This projection is shown at 9 and extends from the web 8 diagonally beneath the adjacent part of the base 5, so that the end of the projection is in a vertical plane extending longitudinally of the base and approximately centrally thereof. The particular shape given 85 to the line 5^b on which the parts 8 and 9 are cut from the base 5 enables the upper edge 9^a of the projection 9 to engage the slightly inclined bottom of the flange 2 while the bend between the parts 8 and 9 is located 90 sufficiently below the base to enable the end of the flange 2 approximately to fit the space provided between the upper end of the edge 9^a and the bottom of the part of the base thereabove, with its end in engagement with the edge 8^a of the part 8. This particular 95 arrangement and inclination of the projection 9 which enables its inner end to lie beneath the central portion of the adjacent 100

105

- part of the base 5 prevents the clamps when applied to the flanges 2, from being overturned by the weight of the flange 6 acting at one edge of the base, even though the 5 beams should be inclined longitudinally; it also secures a firm engagement between the base 5 on the one side, and the projection 9^a on the other side, against the edge portion of the flange 2.
- 10 The bases 5 project a sufficient distance beyond their flanges 6 to enable the clamps to be applied to beams the top flanges of which vary considerably in width, the length of the bases enabling flanges 5^a of varying width to be struck therefrom and to engage the faces of the beam webs 1, thereby to retain the opposite ends of the clamps in engagement with the adjacent edges of the beam flanges 2.
- 15 Having thus described my invention, what I claim is:—
1. As an article of manufacture, a clamp adapted to fasten a metal sheet to a structural beam, said clamp comprising a base adapted to rest on top of a flange of the said beam, a vertical flange extending from said base and having a top edge adapted to engage the bottom of such sheet and provided with a tongue adapted to be passed through said sheet thereby to secure the same against such edge, the said vertical flange having a vertical extension located beyond one end of the base, said extension being provided with a projection extending beneath and spaced from the adjacent portion of the base thereby to engage the bottom of the beam flange while the base engages the top of the said beam flange. 20
2. As an article of manufacture, a clamp for fastening a metal sheet to a structural beam, said clamp comprising a flat base adapted to rest on top of a flange of the said beam, a vertical flange extending from one edge of said base and having a top edge adapted to engage the bottom of such sheet and provided with a tongue adapted to be passed through said sheet thereby to secure the same against such edge, the said vertical flange having a vertical extension located beyond one end of the base, said extension being provided with a projection extending beneath and spaced from the adjacent portion of the base, the said extension and the projection thereof having edges adapted to engage the edge and the bottom of the said beam flange while the base engages the top thereof. 25
3. As an article of manufacture, a clamp for fastening a metal sheet to a structural beam, said clamp comprising a flat base adapted to rest on top of a flange of the said beam, a vertical flange extending from said base and having a top edge adapted to engage the bottom of such sheet and provided with a tongue adapted to be passed through said sheet thereby to secure the same against such edge, the said vertical flange having a vertical extension located beyond one end of the base, said extension being provided with a projection extending at an angle from such extension and beneath and spaced from the adjacent body portion of the base, the upper edge of such projection being shaped to engage the bottom of the beam flange to which the said base is applied and the end of the base opposite such projection being extended beyond the vertical flange whereby such end of the base may be bent into engagement with the opposite side of the beam. 30
4. As an article of manufacture, a clamp for fastening a metal sheet to a structural beam, said clamp comprising a flat base adapted to rest on top of a flange of the said beam, a vertical flange extending from one edge of said base and having a top edge adapted to engage the bottom of such sheet and provided with a tongue adapted to be passed through said sheet thereby to secure the same against such edge, the said vertical flange having a vertical extension located beyond one end of the base, said extension being provided with a projection, the projection extending at an angle from such extension and beneath and spaced from the adjacent body portion of the base, the said projection being adapted to engage the bottom of the beam flange while the base rests on top of the same against such edge, the said vertical flange having a vertical extension located beyond one end of the base, said extension being provided with a projection extending at an angle from such extension and beneath and spaced from the adjacent body portion of the base, the upper edge of such projection being shaped to engage the bottom of the beam flange to which the said base is applied and the end of the base opposite such projection being extended beyond the vertical flange whereby such end of the base may be bent into engagement with the opposite side of the beam. 35
5. As an article of manufacture, a clamp for fastening a metal sheet to a structural beam, said clamp comprising a flat base adapted to rest on top of a flange of the said beam, a vertical flange extending from said base and having a top edge adapted to engage the bottom of such sheet and provided with a tongue adapted to be passed through said sheet thereby to secure the same against such edge, the said vertical flange having a vertical extension located beyond one end of the base, said extension being provided with a projection, the projection extending at an angle from such extension and beneath and spaced from the adjacent body portion of the base, the said projection being adapted to engage the bottom of the beam flange to which the said base is applied. 40
6. As an article of manufacture, a clamp for fastening a metal sheet to a structural beam, said clamp comprising a flat base adapted to rest on top of the said support, a vertical flange extending from said base and having a top edge adapted to engage the bottom of such sheet and provided with a tongue adapted to be passed through said sheet thereby to secure the same against such edge, the said flange having a vertical ex- 45

tension which is provided at its lower end with a projection extending angularly therefrom beneath the adjacent part of the base, the said extension and the top of the said 5 projection being adapted to engage respectively the edge and the bottom of the beam flange with the base resting on top of such flange, the opposite end of the base being extended beyond the vertical flange whereby it may be bent down into engagement 10 with the opposite side of said beam.

In testimony whereof, I hereunto affix my signature.

JAMES F. LOUCKS.
